UNITED STATES PATENT OFFICE.

CYRIL GEORGE MANCHA BENNETT, OF LONDON, AND SYDNEY HERBERT SMITH, OF WEST EALING, ENGLAND, ASSIGNORS TO SMOKELESS ECONOMISERS LIMITED, OF LONDON, ENGLAND.

OIL-FUEL BURNER.

1,144,021.

Specification of Letters Patent. Patented June 22, 1915.

Application filed October 11, 1913. Serial No. 794,637.

To all whom it may concern:

Be it known that we, CYRIL GEORGE MANCHA BENNETT, a subject of the King of Great Britain, residing at 112 Holland road, 5 in the county of London, England, and SYDNEY HERBERT SMITH, a subject of the King of Great Britain, residing at 24 Bradley Gardens, West Ealing, in the county of Middlesex, England, have invented new and useful Improvements in Oil-Fuel Burners, of which the following is a specification:

Our invention relates to oil fuel burners designed more particularly for burning heavy oils and capable of being easily fitted 15 to existing coal furnaces and applicable particularly for use with those furnaces where chain grate stokers are used and where refractory arches are used in the construction of the combustion chamber.

Our invention is characterized by a steam jacketed burner so constructed that the steam forming the steam jet of the burner first enters the jacket passing all around an annular space which surrounds the outer shell of an oil chamber and thereby heating 25 the oil contained therein and then passes out of the jacket and again reenters the burner through a steam pipe which is carried through an air chamber formed by the outer 30 extremity of said burner, to a central circular chamber surrounded by said oil chamber and steam jacket where the end of said steam pipe is converted into a steam nozzle. In 35 the burner of our invention the same steam first heats the oil and then the air entering the central chamber in said burner from its exterior end and thus provides for an absolute uniformity of temperature of the air, steam and oil at the burner mouth. The 40 steam jacketed oil fuel burner of our invention comprises a hollow oil controlling valve with a spindle sleeve extending beyond the burner casing, the interior of said sleeve forming the passage for an interior air supply induced by a steam jet mounted in such 45 a position in said sleeve to give an adequate supply of air mixed with steam with a high velocity before reaching the ignition point of the burner.

Our invention is illustrated by way of example in the accompanying drawings, in which—

Figure 1 shows a sectional elevation of the burner. Fig. 2 shows a front elevation. 55 Fig. 3 shows a section on the line A—B look-

ing in the direction of the arrow. Fig. 4 shows a section on the line C—D looking in the direction of the arrow, and Fig. 5 shows a detail view of the oil valve face.

Referring now to the drawings—the oil fuel burner of our invention does not require high oil pressure and is capable of being fitted in the wall 4 of the furnace as shown in Figs. 1 and 2 conveniently above the front arch by means of the stays 6, the free extremities of which are adapted to be bolted to the lugs 7 projecting from the sides of said burner, shown in Fig. 4.

As shown more particularly in Figs. 1 and 4, the burner comprises a hollow cylindrical casing 1 adapted to form a steam jacket encircling an oil reservoir 2 surrounding a circular chamber 3 in the center of the burner. The said oil reservoir 2 is adapted to receive oil from a tank (not shown) preferably placed on top of the burner with sufficient head to allow the oil to flow freely down to the burner mounted on the front wall 4 of said furnace through a connection 5 shown in Fig. 2. The inner wall of said reservoir 2 is formed by a longitudinally movable sleeve 8 provided at its extremity with a flange 9 in which is arranged a series of slots 10 as shown more particularly in Figs. 1 and 5, if the burner is to be used for thick oil. The oil is adapted to pass out through said slots 10 against the conical inner face of an inwardly turned lip 11 of said burner casing 1 forming the mouth of the burner. The conical outer surface of said slotted flange 9 at the extremity of the oil reservoir 2 is adapted to engage with the conical inner face of said lip 11 and forms therewith an oil valve and its seating. The slots 10 through the flange or valve head 9 allow the oil to pass freely in fine jets against the inner face of said lip 11, thus forming a film of oil the outlet of which at the burner mouth is controlled by the space between the surfaces of said flange or valve head 9 and lip 11. The said sleeve 8 is screwed into the interior of the burner casing and is capable of longitudinal adjustment by means of the hand wheel 12 mounted on said sleeve beyond said burner casing. By this arrangement the slots 10 formed in the flange or valve head 9 are protected by the valve seating formed by the inner conical face of the lip 11 and although the oil is heated to the proper temperatures by the super-heated

steam surrounding the oil reservoir there is little possibility of said slots being blocked up by the carbonizing of the oil. The quantity of oil spray ejected by the burner is controlled by said oil valve and not by the size of the slots in said flange or valve head so that the area of said valve slots need not be limited to the maximum discharge required. If therefore, one or more holes become blocked up the valve can be easily adjusted so that there is an ample amount of oil discharged to keep the burner going. The exterior face 13 of said lip is preferably bell mouthed as shown in Fig. 1. The steam is taken from any convenient place and is conveniently of the same pressure as the steam in the boiler. The steam enters the burner casing 1 through the inlet 122 from the steam pipe 133 which is provided with a steam cock 14 as shown in Fig. 2. From the inlet 122 the steam passes through the hollow interior 15 of the casing which thus forms a steam jacket surrounding and heating up to the temperature of the steam, the oil contained in the oil reservoir 2. From the steam jacket 15 the steam passes out through the outlet 16 and steam pipe 17 to an outlet at the end of said steam pipe, said outlet being formed into a fine nozzle 18, whereby a jet of high velocity is induced in the central circular chamber 3 of the burner which is surrounded by said oil reservoir 2 as shown in Figs. 1 and 4 of the drawings. The said steam pipe 17 passes through the conical air chamber 20 arranged at the outer extremity of the burner as shown in Figs. 1 and 2. As shown in Fig. 1 the said conical air chamber 20 is mounted on the exterior end of the sleeve forming the oil reservoir 2 and oil valve as above described. The inner end of said air chamber 20 is provided with a series of air holes 21 adapted to be moved in or out of register with a corresponding series of air holes 22 formed in a flange 23 projecting from said pipe 17, said flange being adapted to close the exterior end of the chamber 3 surrounded by the said sleeve 8 forming the oil reservoir and within which sleeve 8 the steam nozzle 18 of high velocity is arranged. As shown in Fig. 1 we prefer to arrange additional air holes 24 in the body of said sleeve adapted to be opened or closed by the overlapping flange 25 of said air chamber 20 which is provided with corresponding air holes 26.

The steam first enters the jacket 15 passing all around the exterior surface of the oil reservoir 2 and thus heating the oil contained therein to its own temperature before passing out of said jacket through the outlet 16 and steam pipe 17 by which it is carried through the air chamber 20 to the steam nozzle at the end of said pipe 17 mounted in the central circular chamber of said burner encircled by said oil reservoir and steam jacket. By this arrangement the same steam heats the oil and then the air entering the central circular chamber through the conical air chamber 20 and thus gives absolute uniformity of temperature in the final mixture of air, steam and oil burnt at the mouth of the burner. The said steam nozzle 18 is mounted in the said circular chamber 3 in such a position that the cone of steam passing from the nozzle expands in diameter until on reaching the burner mouth it corresponds in diameter with that of the enlarged end of the conical valve seat and thus carries away the whole film of oil which is allowed to escape from said valve.

The oil fuel burner of our invention has a controlled air supply which passes straight through the burner from end to end without angles or bends, thus tending to increase the final velocity of the mixture of steam and air.

The action of the steam jet is to create a vacuum in the central circular chamber 3 and by means of the air holes the air rushes into said space after being heated in the conical chamber 20 and finally by the steam itself and is thoroughly mixed with the steam before reaching the point of ignition at the mouth of the burner. The velocity of the air is considerably increased by the cone shaped chamber 20. The oil after being brought up to a high temperature by the steam jacket is discharged in fine jets against the conical valve seat 11, the result being that the combined hot air and steam jet effectively mixes with the film of oil as it is discharged at the mouth of the burner and carries it along to the point of ignition in the furnace combustion chamber.

Owing to the air chamber 20 being capable of adjustment so as to move the pairs of air holes 21 and 22, 24 and 26 more or less in or out of register the amount of air entering the circular chamber 3 is controlled.

At the end of the burner casing we may arrange a loose fitting sleeve 30, the end of which is coned to register with the cone face 32 on the plate 4 around the burner aperture 31 in said plate and form with said face 32 an air valve, by which means the outside air supply passing into the furnace around the burner is controlled.

What we claim is:

1. A steam jacketed oil-fuel burner comprising an outer casing, a steam jacket formed in said outer casing, an oil reservoir within said casing concentric with said outer casing and said steam jacket, and having a forwardly extending portion forming a hollow oil controlling valve, an air chamber at the exterior end of the burner, a central air chamber in said burner surrounded by said oil reservoir, a steam nozzle mounted in said air chamber, and an outlet steam pipe

- leading from said steam jacket through said air chamber to said steam nozzle.
2. A steam jacketed oil fuel burner comprising a steam jacket, a spindle sleeve extending beyond the steam jacket, an air chamber for an interior air supply formed by the interior of said sleeve, a steam pipe extending longitudinally through said air chamber and adapted to heat said air by radiation, a steam nozzle mounted in said sleeve at the end of said steam pipe for inducing said air supply, and means for conveying the steam from the steam jacket to said radiating steam pipe.
3. A steam jacketed oil fuel burner, comprising a steam jacket having a valve seat, a hollow oil controlling valve co-operating therewith, a spindle sleeve formed by an extension of said oil valve and extending beyond the steam jacket, a passage for an interior air supply formed by the interior of said sleeve, a steam pipe adapted to heat said air supply by radiation, a steam nozzle at the end of said steam pipe for inducing said air supply, a conical air chamber rotatably mounted at the exterior end of said spindle sleeve, and means controlled by the rotation of said chamber for governing the

supply of air to the interior of said spindle sleeve.

4. A steam jacketed oil fuel burner comprising in combination, a furnace plate provided with a burner opening having an outwardly flared conical wall, a steam jacket, an annular oil reservoir having an inner wall ²⁵ formed as a longitudinally movable sleeve the end of which co-operates with the end of the steam jacket to form a burner opening, and a longitudinally adjustable member co-operating with said burner and provided ⁴⁰ with a conical end portion co-operating with said conical opening in the furnace plate, to form a valve, whereby the outside air supply is caused to enter the furnace at the mouth of the burner in the form of a conical ⁴⁵ stream, variable in volume but constantly converging toward the blast of burning oil.

In testimony whereof we have signed our names to the specification in the presence of two subscribing witnesses.
